MINER'S SAFETY HELMET CAP

Filed Feb. 23, 1928

FIG. 2.

FIG. 3.

Inventor
J. Vanusek.

By *Alvarez, Jr.*
Attorney

UNITED STATES PATENT OFFICE.

JOHN VANUSEK, OF REPUBLIC, PENNSYLVANIA.

MINER'S SAFETY HELMET CAP.

Application filed February 23, 1928. Serial No. 256,424.

The invention relates to a head covering particularly for use by miners while following their occupation and has for its principal object the provision of a head covering including an insert for a miner's cap that is padded and provided with a plate of metal, preferably aluminum and padded to prevent injury to the head of the miner while at work because of particles of dirt and stone falling on the miner's head.

A further object of the invention is the provision of an insert for miners' caps comprising a hollow body made of two layers of flexible material secured together at their edges and spaced apart to receive a cushion filling, the outermost of said layers being preferably of a material that is a non-conductor of electricity and having secured thereto a metal plate, preferably of aluminum, and secured on the inner side of the outer layer with a layer of flexible material of non-conductor of electricity covering the inner side of the plate, said insert being adapted to be secured in a miner's cap to shield the head of the miner from injury by falling dirt, stones, etc. from the roof of the mine.

The invention will be described in detail hereinafter and will be found illustrated in the accompanying drawings, in which

Figure 1 is a longitudinal sectional view of a miner's cap showing the insert in position therein,

Figure 2 is a top plan view of cap, and

Figure 3 is a fragmental front elevation of the cap.

In the drawings similar reference characters are used to designate corresponding parts throughout the several views.

The invention, as heretofore stated, relates to an armored insert for miners' caps, designated 1, that is preferably made of leather, but may be made of any suitable material, and the insert designated 2 is adapted to be secured in the cap in any suitable manner. The insert 2 consists of an outer layer 3 made of sheet rubber or other non-conductor of electricity, and an inner layer, forming the lining of the cap, of any flexible material, designated 4, but preferably of fabric.

Secured to the inner side of the outer layer 3 is a concaved plate 5 of metal, preferably aluminum, and 6 designates a layer of rubber or other flexible material that is also a non-conductor of electricity and arranged to cover the inner side of the plate 5. The layers 3, 5, and 6 are secured together by means of rivets 7 or any other suitable manner, and the edges 8 of the layer 6 are vulcanized or otherwise secured to the layer 3. 55 The edges of the outer layer 3 and the lining layer 4 are secured together as shown at 9 in any suitable manner. The space between the layers 3 and 6 and the lining layer 4 is filled with cushion material such for instance as cotton, felt, shredded asbestos, or the like, 65 designated 10. The peak or top of the cap 1 and the insert 2 is provided with a plurality of ventilating openings 11, that may if desired be defined by tubular members. 70

It will be understood that the concaved plate 5 and the cushion filling 10 will protect the head of the miner from injury by falling material from the roof of the mine, and that the layers 3 and 6 being of material that is a non-conductor of electricity will protect the head of the miner from shocks by engagement with electric wires in the mines. The visor of the cap is indicated at 12, and 75 13 is an angular bracket member secured to the cap and to the visor 12 to hold a lamp, 14 indicating a loop to be engaged by the bracket on the lamp, while the upper portion of the bracket is provided with openings 15 in which may be secured an electric lamp. 80 16 indicates a strap on the rear of the cap and provided with a detachable fastening member 17 a mating member 18 of the cap to form a loop to provide a guide for the electric wire from a battery carried by 85 the miner to the lamp, not shown.

What is claimed is:—

An armored head covering, comprising a removable insert for a hat or cap, consisting of a hollow body adapted to completely line 95 the inside of the hat or cap and to envelop the upper part of the head, said body formed of spaced layers of flexible material having their edges secured together, the space between said layers provided with 100

cushion material and adapted to protect the top and sides of the head, the outer layer being of a material that is a non-conductor of electricity, a plate of rigid material secured to the inner side of said outer layer, a layer of flexible material that is a non-conductor of electricity covering the inner side of said plate, and driven fastenings secured through said plate and the layers of flexible material enclosing the plate. 10

In testimony whereof I affix my signature.

JOHN VANUSEK.
